UNITED STATES PATENT OFFICE.

CHARLES C. STEWART, OF DETROIT, MICHIGAN.

SUPPORTING DEVICE.

1,280,325.

Specification of Letters Patent.

Patented Oct. 1, 1918.

Application filed March 23, 1918. Serial No. 224,334.

To all whom it may concern:

Be it known that I, CHARLES C. STEWART, a citizen of the United States, residing at Detroit, in the county of Wayne and State 5 of Michigan, have invented certain new and useful Improvements in Supporting Devices, of which the following is a specification, reference being had to the accompanying drawings.

10 This invention relates to an improved flash lamp support and has for its primary object to provide a convenient and serviceable device which is particularly designed for use by musicians whereby the music note 15 sheet or page may be properly illuminated at night in order to enable the musician to clearly discern the printed characters.

It is another and more particular object 20 of the invention to provide a device for the above purpose embodying a supporting standard, and means for detachably mounting or clamping the standard upon the wind tube of a musical instrument, or other fixed supporting part in suitably spaced relation 25 to a music sheet holder or clamp, and means for adjustably mounting an electrical flash lamp upon the standard whereby the light rays from the lamp will be properly disseminated over the printed page.

30 And it is a further general object of the invention to provide an electric flash lamp support as above characterized which will be highly serviceable and convenient in practical use, and consists of relatively few 35 parts of very simple construction, and can be manufactured and sold at comparatively small cost.

With the above and other objects in view, the invention consists in the improved construction, combination and arrangement of 40 the several parts as will be hereinafter more fully described, subsequently claimed and illustrated in the accompanying drawing in which similar reference characters designate 45 the corresponding parts throughout the several views, and wherein:

Figure 1 is a side elevation of a musical wind instrument illustrating the preferred embodiment of my improved lamp support 50 applied thereto;

Fig. 2 is a section taken on the line 2—2 of Fig. 1;

Fig. 3 is a section taken on the line 3—3 of Fig. 2; and

55 Fig. 4 is a section taken on the line 4—4 of Fig. 2.

Referring in detail to the drawing, M designates a musical instrument upon which a sheet music holder or clamping device H is suitably mounted or secured in any approved manner. It is to be understood that the present invention is not limited in its application and utility to a musical instrument of the type herein illustrated, but is likewise applicable to various other musical instruments, and may also be mounted and arranged upon a separate supporting frame suitably secured or strapped upon the chest or the arm of the musician.

As herein shown, the improved lamp support includes a clamp consisting of two semi-circular sections designated 5 and 6 respectively, which are hingedly connected to each other at one of their ends as at 7. At its other end each section of the clamp has a lug 8 suitably fixed to the outer face thereof. A clamping screw 9 is carried by the lug 8 on the band section 6 and is adapted for threaded engagement in an opening in the lug 8 on the other band section 5. To the outer face of this latter band section and centrally thereof a rectangular sleeve 10 is suitably fixed, said sleeve being provided with an arm or extension 11 having a threaded bore to receive the set screw 12.

The lamp supporting standard 13 has one of its ends laterally extended to provide an angular arm 18 adapted for engagement in the sleeve 10 on the sectional clamp. By adjusting the screw 12 into binding engagement upon this arm, the standard may be rigidly held in its assembled position against shifting movement relative to the attaching clamp. This standard throughout its length is of rectangular form.

14 designates an electric flash lamp which may be of any ordinary or approved form and construction. Upon one side of the lamp casing a rectangular metal sleeve 15 is suitably fixed and is adapted to receive the standard 13. A boss or projection 16 is formed on the outer side wall of said sleeve and has a threaded bore to receive the clamping or set screw 17. It will thus be apparent that after the lamp has been vertically adjusted and properly positioned on the standard 13, the set screw 17 may be adjusted into binding engagement with the standard to securely hold the lamp against movement from its adjusted position.

As herein shown, the attachment is applied in operative position, by arranging the

sections 5 and 6 of the clamp upon opposite sides of the wind tube of the instrument, and then adjusting the screw 9 to tightly clamp said sections on the tube. The angular end 5 of the standard 13 is then inserted in the sleeve 10 on the clamping band by means of the screw 12. Finally, the lamp 14 is properly adjusted upon the standard 13 so that the diffused rays of light will properly strike 10 upon the music sheet in the holder H and illuminate all portions thereof so that the characters will become clearly visible. The lamp is then securely fixed or held in its adjusted position on the standard by tightening 15 the set screw 17. The supporting standard and the lamp thereon can be easily and quickly moved or adjusted toward or from the music sheet holder by simply loosening the screw 9 and shifting the sectional band 20 clamp in the proper direction upon the tube of the instrument and then again tightening said screw.

From the foregoing, it will be seen that I have devised a very simply constructed and 25 serviceable attachment whereby the electric flash lamp can be easily and quickly applied in operative position and properly adjusted with respect to the music sheet holder. As above stated, the device may be readily applied to various other musical instruments than that herein illustrated or to a supporting means strapped or otherwise attached to the body or arm of the musician. To this 30 end, several different forms and sizes of the 35 sectional attaching clamp upon which the standard is mounted, may be provided. The various parts of the lamp support, are of simple and durable construction, and when assembled in operative position will not seriously interfere with the line of vision of the 40 musician or the proper operation of the instrument. When not in use, the several parts of the device can be readily disassembled and compactly arranged in a case or 45 other receptacle. The device can also be manufactured and sold at relatively small cost.

Copies of this patent may be obtained for five cents each, by addressing the "Commissioner of Patents, Washington, D. C."

While I have herein shown and described the preferred construction and arrangement of the various parts, it is to be understood that the same are susceptible of considerable modification and I therefore reserve the privilege of adopting all such legitimate changes as may be fairly embodied within the spirit and scope of the invention as 55 claimed.

Having thus described my invention, what I claim is:—

1. A support of the character described including an attaching clamp adapted for 60 detachable engagement upon a stationary part, said clamp being exteriorly provided upon one side with a sleeve, a standard having an angular end portion adapted for engagement in said sleeve, a set screw for hind- 65 ing engagement with the angular end of the standard, in combination with a lamp having a sleeve upon one side for engagement upon the standard, and means carried by the sleeve to engage the standard and secure the 70 said lamp in its vertically adjusted position on the standard.

2. A supporting device of the character described including an attaching clamp adapted for detachable engagement upon a 75 stationary part, said clamp having a rectangular sleeve secured to one side thereof, a supporting standard having an angular end portion adapted to be engaged in said sleeve, means to coact with the angular end of the 80 standard and secure the same within the sleeve, in combination with a lamp, a sleeve secured to one side of the lamp casing to receive said standard, and a set screw carried by said sleeve to coact with the standard and 85 secure the lamp in its vertically adjusted position on the standard.

In testimony whereof I hereunto affix my signature in the presence of two witnesses,

CHARLES C. STEWART.
